UNITED STATES PATENT OFFICE.

SAUL GRABOFF, OF NEW YORK, N. Y.

CIGAR-CUTTER.

1,111,743.

Specification of Letters Patent. Patented Sept. 29, 1914.

Application filed March 16, 1914. Serial No. 825,063.

To all whom it may concern:

Be it known that I, SAUL GRABOFF, a citizen of the United States, and a resident of the borough of Manhattan, city, county, and State of New York, have invented certain new and useful Improvements in Cigar-Cutters, of which the following is a specification.

My improvements relate to devices for 10 clipping off the ends of cigars, and known technically as cigar cutters, adapted for personal use, and to be carried in the pocket for the convenience of the owner.

The invention consists in the specific construction and arrangement of parts described and claimed whereby the release and manipulation of the cigar cutter blade is simplified and rendered more convenient and effective; whereby one or more auxiliary 20 blades are combined with the cigar clipping device; and whereby the rivets which secure the parts together are made to perform additional functions, all as hereinafter fully set forth.

25 In the accompanying drawings, Figure 1, is an elevation of my improved device taken on the side on which the cigar cutter is located; Fig. 2, an elevation with the side plate removed, and the cigar cutter blade in locked position; Fig. 3, a like view with the cigar cutter in released position, and ready for action, the fingers of the user being indicated by dotted lines; Fig. 4, is an edge view of the device; Fig. 5, an elevation of the reverse 35 side of the device, on which the knife blades are located; Fig. 6, an elevation with this side plate removed. Fig. 7, is an elevation of my improved device with both blades open and the cigar cutter released.

40 In the construction shown in the drawings α , designates the center plate of the structure and α' , and α'' , the parallel side plates, all three plates being of the same general configuration, including the coinciding circular openings b , for the cigar tip.

The side plate α' , is spaced apart from the central plate α , by the shank s' , of the duplex spring s ,—said shank being positioned medially between its two spring tongues s^2 , s^3 , and being held in position by the two rivets r' , r'' . The spring tongue s^3 , engages with the short arms of the cutter lever or plate C , fulcrumed on the rivet r^3 . This cutter plate C , is formed to straddle the lateral shank s' , of the duplex spring s , as shown in Figs. 2 and 3, and its free end is formed with

the cutter blade c , which normally closes the cigar tip aperture b , being held in such closed position within and between the middle plate α , and the side plate α' , by a latch d , pivoted on the rivet r^4 , and controlled by the free end s^2 , of the duplex spring s . That is to say, the said end s^2 , of the spring s , bears constantly against the short arm d' , of the latch d , tending constantly to hold it 60 against the rivet r^5 , which acts in this respect as a stop or shoulder to limit the thrust of the latch under the pressure of the spring s . In this normal position the hooked end d^2 , of the latch d , will engage the shoulder c' , 65 on the cigar cutter blade C , if the latter is depressed,—the edge c^2 , of the blade c , acting as a cam surface against the ends d^2 , of the latch d , to force back said latch against the resistance of the spring arm s^2 , during 70 the depression of the plate C . The latter tends constantly to spring open into the position shown in Fig. 3, by reason of the engagement of its shoulder c^3 , with the end s^3 , of the spring s ,—said end s^3 , of the spring 75 also acting as a stop to limit the outward thrust of the blade plate C , when the shoulder c^4 on the cutter plate contacts therewith as shown in said Fig. 3, which also illustrates in dotted lines a convenient method of 80 holding and manipulating the device single handed. That is to say, for instance, by grasping the device in the right hand between the index finger and the thumb, both the latch d , and the cutter blade C , are in 85 convenient control of the user, so that by pressing the roughened end of the short arm d' , of the latch d , the cutter blade may be 90 released into the position shown in Fig. 3, to be depressed by the thumb and automatically locked in closed position by the latch d ,—the depression of the blade plate C , of course, causing the cutting blade c , to clip off the tip end of a cigar previously inserted in the openings b . This utilization of the 95 short arm d' , of the latch d , as a means for conveniently retracting the latch d , to release the cutter plate C , is a distinctive feature of my construction, and is effected by placing the fulcrum r^4 , a sufficient distance 100 from the roughened contact surface of the latch to insure the requisite leverage to release the cutter plate with but slight exertion on the part of the user.

Between the central plate α , and the side plate α'' , is mounted another duplex spring e , the basic shank e' , of which is secured by

the rivets r^4 , r^5 , said shank e' , thus acting as a spacing block between the said two plates a , a^2 . It will be noted incidentally in this connection that the rivet r^4 , also acts 5 as the fulcrum for the latch d , while the rivet r^5 , acts as the stop rest therefor as shown in Figs. 2 and 3. The ends of the attenuated arms, e^2 , e^3 , of the duplex spring e , act as controllers for the blades h , h' , engaging with the angular shanks of the latter and holding them in prescribed positions until forcibly turned upon their pivots r^6 , r^7 , against the resistance of said spring arms as in the case of ordinary pocket knife 10 blades &c. These pivots r^6 , r^7 , also act as rivets to secure the plates a , a' , a^2 , together at that end of the device; and the blades h , h' , may be adapted for use as auxiliary 15 cigar cutters, as finger nail blades or like uses, one, if preferred, being roughened or formed for use as a file, as h' ; or either or both of the blades may be specially shaped for other particular purposes and uses, as may be found most expedient in adapting 20 the device to the requirements of trade. 25

The arms a^2 , a^3 , of the spring are positioned against undue spread by the rivets r^1 , r^2 , by which the cigar cutter blade spring s , is secured in position, said rivets thus 30 forming a double function. By thus utilizing the rivets r^1 , r^2 , r^3 , r^4 , r^5 each for a double function I am enabled to greatly simplify and cheapen the structure of my device, at the same time rendering it compact, 35 durable and effective.

The ease with which the cigar tip cutting mechanism may be manipulated by one hand, leaving the other free to hold and present the cigar for cutting, I believe to 40 be a distinctive result of my special construction and arrangement of parts as compared with the prior state of the art, and it is a feature of commercial importance.

By providing one or more knife blades in 45 conjunction with the cigar tip cutter I greatly increase the usefulness of the device without impairing its utility as a cigar cutter, but rather increasing such special utility, as it is frequently desirable to cut off 50 the end of a cigar the tip of which is too thick for insertion in the openings b . Furthermore, one or more blades are always conveniently available for an infinite vari-

ety of uses, as for sharpening pencils, cleaning or trimming finger nails, cutting cord 55 &c.,—the device as a whole forming an ideal pocket implement for masculine wear and use.

What I claim as my invention and desire 60 to secure by Letters Patent is—

1. In a device of the character designated, parallel plates having tip-receiving openings, a pivoted blade, a spring pressing said blade to open position, and a latch to hold the blade closed, said spring having an extension operating said latch and the latch disposed at an angle to the blade and co-operating directly with the spring and blade. 65

2. In a device of the character designated, parallel plates, a cigar tip cutter blade movably mounted between said plates, a spring pressing said blade to open position, and a pivoted latch to hold said blade closed said spring having an extension operating said spring, and the blade having a cam surface 75 engaging the latch to force it back against the pressure of the spring.

3. In a device of the character designated, plates, a cigar tip cutter blade pivoted therebetween, a spring pressing the blade to open 80 position, a latch to hold the blade closed, said spring having an extension operating said latch, and the blade having a cam surface for engagement with the latch, and means between the plates in the path of the 85 latch to limit the thrust of the latter under the influence of the spring.

4. In a device of the character designated, the combination of parallel plates formed 90 with cigar tip openings, a duplex spring interposed between them, the shank of which acts as a spacing block, a cigar tip cutter blade fulcrumed on a rivet between said plates and engaging with one end of said duplex spring and a latch pivoted on a rivet 95 between said plates and resting normally against another rivet there-between and controlled by the other arm of said duplex spring, and adapted to engage with a shoulder on the said cutter blade, for the purpose described. 100
